UNITED STATES PATENT OFFICE.

HERMAN N. KENNEDY, BURE A. KENNEDY, AND JOHN F. STEWARD, OF CHICAGO, ILLINOIS.

GRAIN-HARVESTER.

SPECIFICATION forming part of Letters Patent No. 351,268, dated October 19, 1886.

Application filed October 19, 1885. Serial No. 120,261. (No model.)

To all whom it may concern:

Be it known that we, HERMAN N. KENNEDY, BURR A. KENNEDY, and JOHN F. STEWARD, citizens of the United States, residing at Chicago, in the county of Cook and State of Illinois, have invented certain new and useful Improvements in Grain-Harvesters, which are fully described in the following specification.

This invention relates to the general construction of a grain-harvester.

It comprises novel form of the longitudinal and transverse bars of the frame, novel mode of securing the same together and to the upright portions of the frame, novel form of the junction-pieces, whereby they afford bearings for the gearing, and novel location of the gearing.

In the drawings, Figure 1 is a plan. Fig. 2 is an outer side elevation. Fig. 3 is a front elevation, the pole being shown in vertical section. Fig. 4 is a rear elevation. Fig. 5 is an outer side elevation of the outer truss and segment and the gearing having its bearings on and adjacent thereto. Fig. 6 is an inside elevation of the inner truss and segment and raising and lowering screw thereon. Figs. 7, 8, 9, and 10 are perspectives, respectively, of the outer rear, outer front, inner rear, and inner front junction-pieces of the wheel-inclosing frame. Fig. 11 is a perspective of a bushing or thimble which forms a bearing for the sickle crank-shaft. Figs. 12 and 13 are respectively front and rear elevations of a certain A-frame which sustains the elevator. Fig. 14 is a rear elevation of the platform. Fig. 15 is a vertical section through $v v$ on Fig. 14. Fig. 16 is a detail elevation of the inner segment and truss and raising and lowering mechanism.

A is the front sill or frame bar, and A' is the rear sill or frame bar. Both are made of tubular metal, and in practice iron gas or water pipe is used for the purpose. They are secured together by the trusses B and B', the former outside and the latter inside the drive-wheel.

C and C' are respectively the outer and the inner segments, which are secured to the trusses B and B', respectively, in such manner as to constitute the struts for the same.

The truss B comprises the upper and lower bars, b b, and the clips D' and D², which unite said bars at their ends, and the truss B' comprises the similar bars, b' b', and the clips D³ and D⁴, uniting the ends of said bars. The beams b b and b' b' of the trusses B and B' are formed of angle-iron, secured together at the ends or angles of the trusses by the angle-clips D' D² and D³ D⁴. Said clips are provided with tubular sockets or apertures d¹⁰ d²⁰ d³⁰ d⁴⁰, to receive the sills A A' and afford the means of securing the trusses to the sills. They have also the several bearings for the gearing and the raising and lowering mechanism, as hereinafter fully explained in detail.

E is the drive-wheel. e is its hub. e' is the axle. The wheel is loose on the axle, and the latter has pinned fast to it the pinions E' E', meshing with the racks c c' of the segments C C'. Said axle e' has also pinned fast to it the sprocket-wheel E², and the drive-wheel E has formed integral with its hub e the sprocket-wheel E³.

The rear sill, A', is made to serve as the axle upon which is journaled the beveled gear-wheel F, whose web F' is made bell-shaped, for a reason hereinafter explained, and whose hub F² is elongated into a sleeve, as illustrated, and has integral with it the sprocket-wheel F³, in the same vertical plane with the sprocket-wheel E³. The endless chain f³ passes around the two sprocket-wheels E³ and F³ and communicates motion from the former to the latter. The rear sill, A', also serves as the shaft upon which is journaled the sprocket-wheel G in the same vertical plane with the sprocket-wheel E², and having integral with it the worm-wheel G'. The clip D³ has the tubular aperture d³⁰, to receive the sill A', and is bolted firmly to said sill by the bolts d', which pass entirely through both the clip and the tubular sill A'. In a plane at right angles to the aperture d³⁰, said clip has the two bearings d¹¹ d²¹, in which is journaled the crank-shaft H, which is provided between said bearings with the endless screw or worm H'. Said worm meshes into the worm-wheel G', and by the rotation of the crank-shaft H said worm is made to communicate motion to the said worm-wheel G'

and rotate thereby the sprocket-wheel G. The endless chain g passes around the sprocket-wheels G and E², and the rotation of the former, as described, rotates also the latter and 5 the axle e' and the pinions E E', and by the engagement of the latter in the racks c c' of the segments C C' raises or lowers the entire frame on the axle. The wheels F³ and G having 10 their axes coincident, and the same being true of the wheels E² and E', the connection of the gearing with the driving power is not disturbed by this adjustment.

The clip D⁴, which forms the forward end 15 of the truss B, has the tubular aperture d⁴, through which the front tubular sill, A, extends. It is formed on its lower side to fit and receive the finger-bar I, which is bolted to it, the same bolts, i i, also securing the clip D⁴ to the front sill, A. This clip D⁴ has the 20 extension D¹⁰ in front of the sill A, to afford an attachment for the pole J, which is pivoted on the hollow stud j and retained by the head of the bolt j', which passes through the hollow stud j, as seen in vertical section in Fig. 3.

25 As hereinafter explained, the pitman or connecting-rod to the sickle extends in front of the sill A, and the extension D¹⁰ of the clip D⁴ has the opening d¹⁰ of sufficient vertical extent to allow for the play of said pitman, 30 which passes through it.

The clip D⁴ has its tubular socket d¹⁰ extended inward to receive the end of the rear sill, A', and is securely bolted thereto by the 35 bolts d. At right angles to the socket d¹⁰, and in the vertical plane of the beams b b of the truss B, the clip D⁴ has the horizontal bearing for the shaft k, formed by the bushing or thimble k, driven tightly into the clip from the rear. The shaft K extends forward through 40 the center of the truss B, and has a bearing in the front clip, D². A bevel-pinion, K', on the shaft k, meshes with and is driven by the bevel-gear F. Said pinion being small, the shaft K necessarily passes very near to the face or 45 gear-rim of the wheel F. In order, therefore, to afford room for fastening the rear sill, A', which is the axle of the wheel F, securely to said clip D⁴, said gear-wheel F is given the bell-shaped web F', and into this 50 hemispherical shell the socket d¹⁰ of the clip D⁴ extends, and is bolted to the tubular sill, as above described. The bushing k is extended rearward in the tapering end k², and affords a stop for the pinion K', which is loose 55 on the shaft K. Fast on the shaft K, at its rear end, is the sprocket-wheel K², from which power is communicated to the various mechanisms on the harvester-frame. The hub of the pinion K' has the clutch-teeth k¹⁰, and upon 60 the shaft K, between the pinion K' and the sprocket-wheel K², is placed the clutch-wheel K³, revolved by and sliding on the shaft K, and provided with the spring K⁴, tending to hold it in engagement with the clutch-teeth of 65 the hub of the pinion K', whereby the shaft K is revolved. Suitable similar means may be employed to disengage the clutch at will.

The clip D² has the socket d²⁰, for the reception of the end of the front sill, A, which is secured to said clip by the bolts d, as illustrated. At right angles to said socket d²⁰, and 70 in the same horizontal plane, said clip has the box d²¹ for the front end of the shaft K. To the shaft K, in front of the box d²¹, is secured the crank L, which drives the sickle, the shoulder l of the crank forming a stop for the shaft K, to prevent its longitudinal movement to the 75 rear.

The clips D¹, D², and D⁴ are provided, respectively, with the wings d¹³, d²³, and d⁴³, to 80 afford attachments for uprights to sustain the frame-work of the elevator and other elevated mechanism. These uprights M¹, M², and M⁴ are all preferably made of angle-iron. M¹ is secured to the clip D¹. M² is secured to the 85 clip D², and M⁴ is secured to the clip D⁴. The uprights M¹ and M² are connected above the drive-wheel by the horizontal bar M⁵, also preferably of angle-iron. Said horizontal bar is firmly bolted to the upright M² and to the 90 bracket N², (hereinafter described,) which is itself bolted to the upright M¹. Immediately above the point of connection of the bar M⁵ to the upright M², the latter is bent horizontally inward over the drive-wheel, and the upright 95 M⁴ is in like manner bent at m⁴, the said horizontal portions M²¹ and M⁴¹ being parallel, and serving purposes hereinafter explained.

To the rear sill, A', at a short distance inward from the truss-clip D³, is securely bolted 100 the angle-iron bar M³, which is bent first vertically and then horizontally inward, the latter horizontal portion, M³¹, being at the level of and parallel with the horizontal portion M⁴¹ of the upright M⁴. To the upright portion M³⁰ 105 of the bar M³, and to the upper part of the upright M⁴, are secured the rear elevator slide bearing-bars O O, the latter fastening being conveniently made by bolting the sheathings O⁴ to upright and riveting the bars to the sheathing. 110 The latter junction may be effected by means of the sheathing riveted both to the slide-bearing bars and to the said upright; or the latter may be slightly broadened to overlap the ends of the slide bearing-bars and 115 bolted thereto, as shown in dotted lines in Fig. 4, and to the horizontal portion M²¹ of the upright M², and to the upright M⁴—one on each side of the angle m⁴—are bolted the front slide bearing-bars, O' O'. In these slide 120 bearing-bars are journaled the elevator-rollers O² O² O² O² in the customary manner, near the ends of the slide bearing-bars, so that the elevator-canvas and the ribs thereon will pass around the ends of the bars in passing over 125 the rollers.

To the outer surface of the slide bearing-bars O O and O' O' is secured the side sheathing, O⁴ O⁴, which is made of sheet metal. The bolts which secure the slide bearing-bars to 130 the supporting-uprights M¹, M², M³, and M⁴ pass through the metal sheathing O⁴, and said bars M¹ M² M³ M⁴ therefore serve to clamp said sheathing onto the slide bearing-bars. The

sheathing may be further secured by screws, rivets, or nails. While this sheathing adds slightly to the rigidity of the elevator-frame, said frame is complete as to strength without it, the sheathing being only needed as an inclosing-wall and not as a support or to furnish bearings for the elevating mechanism. This mode of construction, depending for strength upon the slide bearing-bars, and thus permitting the use of thin material for inclosing walls, saves the space usually occupied by thick walls, being about one inch and a half, and diminishes by that much the length of all parts—frame-bars, shafts, and chains—which extend from front to rear without diminishing the interior measurement and carrying capacity of the elevator.

It will be seen that the elevator-frame consists, substantially, of two approximately right angled triangles in parallel vertical planes, having their bases horizontal and at the same level, and their right angles and their vertical angles respectively connected rigidly by horizontal cross-bars, the rear triangle comprising the rear sill, A', as its base, the upright M' as its vertical side, and the rear elevator slide bearing-bars O O as its hypotenuse, the front triangle comprising the front sill, A, as its base, the upright M² as its vertical limb, and the front elevator-slide bearing-bars, O' O', as its hypotenuse. The hypotenuse is fastened to the base in the rear triangle by the angle-iron M³, which is secured to both, and in the front triangle by the upright M⁴ and the clip D', secured together, and one fastened to the hypotenuse and the other to the base. For additional security the slant-bars O⁵ O⁶ are added below the slide bearing-bars O' O' and O O, and secured in the same manner to the uprights, respectively. The cross-connections between the two triangles are the trusses B and B', connecting their bases, and the cross-beam M⁵, connecting their vertical limbs near or at the apex, and to this may be added the horizontal cross-bar M⁶, which is secured to the upper end of the upright M' and to the front slide-bar, O'. In order to further stiffen this frame, and particularly to prevent any fore-and-aft strain which may be applied to it, causing torsion of the front and rear sills, A and A', or causing the clips D', D², D³, and D⁴ to slip around on said sills, there are extended from the upper end of the inner segment, C', the braces P', P², P³, and P⁴, the first extending upward and outward and rearward and secured to the uprights M', and the second extending upward and outward and forward and secured to the upright M², the third extending downward and rearward and inward and secured to the rear sill, A', and the fourth extending downward and forward and inward and secured to the finger-bar I. These four braces, together with the portion of the inner segment, to which they are secured as to a center block, are equivalent in effect to two diagonal and intersecting braces secured rigidly together at their intersection in an oblique plane

approximately parallel to that of the hypotenuses of the two-end triangle of the elevator-frame, so that no fore-and-aft strain of that frame can occur without producing direct tensile strain upon one or the other of these diagonal braces and being resisted by the tensile resistance of the same.

It will be further evident that the braces P² and P⁴ tend to brace the sills A' and A, respectively, against horizontal distortion or "swagging" backward and downward; and to further assist in the same preventive office there are provided the braces P⁵ and P⁶, secured to the lower end of the inner segment, C', and extending respectively inward, upward, and forward to the finger-bar I and inward, upward, and rearward to the rear sill, A', said braces being secured to said sills, respectively, at the same points, and conveniently by the same bolts which secure the braces P⁴ and P², respectively, to said sills.

N, N', and N² are brackets which support various parts of the binding-table and mechanism. n and n' are braces for said brackets N and N', and n² is a hanger in line with the bracket N² and designed to support the front end of the binder-frame bar Q, whose rear end bears in the said bracket N². These parts do not pertain to my invention and need not be further described.

R is the seat-plank, supported by being bolted upon the horizontal portions M³¹ and M⁴¹ of the uprights M³ and M⁴.

The rear sill, A', extends the entire length of the rear of the platform S. To its under side is fitted the plank S', hollowed on the upper edge to let in the round sill A', and to the under edge of the said plank is suitably secured the matched flooring S², and both plank S' and flooring S² are secured to the tubular sill A' by the bolts a passing through all three. The plank thus serves as a hanger to connect the flooring to the sill.

The front sill of the platform is formed by the finger-bar I, made of Z-bar iron. To the under side of the lower horizontal lip, i', of this finger-bar is riveted the metal strip I', and the flooring S², being beveled on the under surface at its front edge, forms a butt-joint with the edge of the lip i', which joint is covered by the strip I', which is riveted also to the flooring S².

We claim—

1. In combination with the cylindrical frame-bar, the gear-wheel which communicates power from the drive-wheel to the operating mechanisms of the harvester, having said cylindrical frame-bar as its axle.
2. In combination with the cylindrical frame-bar extending horizontally across the vertical plane of the drive-wheel, the sickle crank-shaft at right angles to said frame-bar, a gear-wheel having said frame-bar as its axle, and a pinion on the sickle crank-shaft meshing with and driven by the gear-wheel on the frame-bar.
3. In combination with the drive-wheel and

- a power-communicating wheel rigid therewith, the frame sustained on the drive-wheel axle having a horizontal cylindrical sill or main frame-bar extending across the vertical plane of the drive-wheel, two wheels formed integral, one inside and the other outside of the vertical plane of the drive-wheel, and having said horizontal cylindrical frame-sill as their axle, a shaft at right angles to the said cylindrical sill, and a pinion thereon, one of said integral wheels having motion communicated to it by the power-communicating wheel on the drive-wheel, and the other communicating motion to the said pinion and its shaft.
5. In combination with the outer truss and the cylindrical frame-bar secured to it, a main driving-pinion, K', and its shaft located in the vertical plane of the truss and the horizontal plane of the cylindrical frame-bar; and a gear 10 wheel, F, having the cylindrical frame-bar for its axle, meshing with and driving the pinion and its shaft, and having the bell-shaped web F', as and for the purpose set forth.
15. In combination with the drive-wheel loose on its axle, the sprocket-wheel rigid with the drive-wheel, the frame having a cylindrical sill, the segments rigid with the frame, the axle having the pinions rigid with it meshing in the segment-racks, the sprocket-wheel rigid with the axle, the sprocket-wheel having the cylindrical sill as its axle, and having the main gear rigid with it, the sprocket-wheel having the cylindrical sill as its axle, and having the worm-wheel rigid with it, an 20 endless screw or worm shaft journaled on the frame and engaging the worm-wheel, and the chains connecting, respectively, the last-named, sprocket-wheel with the first-named, and the intermediately-named with each other, substantially as and for the purpose set forth.
25. In combination with the truss-bars and the cylindrical sills, the truss-clips having the sockets for the sills, the wings to secure the bars, and the bearings for the gearing, substantially as and for the purpose set forth.
30. In combination with the truss-bars and the cylindrical sills, and the frame-uprights, the truss-clips having the sockets for the sills, the wings to secure the bars, the wings to secure the frame-uprights, and the bearings for the gearing.
35. In combination with the front and rear sills, the truss-bars extending from front to rear, and the truss-clips provided with sockets for fastening the sills, and with wings in a plane at right angles to the sockets for securing the truss-bars, whereby the clips form rigid junctions between the sills and trusses.
40. In combination with the tubular front and rear sills and the upper and lower truss-bars, the truss-clips having tubular sockets to receive the sills bolted therein and suitable wings to attach the truss-bars by bolting thereto.
45. In combination with the front and rear sills, the truss-bars extending from front to rear, the uprights, and the truss-clips having the sockets wherein the sills are rigidly bolted, and the wings, respectively, whereto the truss-bars and the uprights are bolted, whereby 70 said clips form the junctions between the sills, truss-bars, and uprights.
5. In combination with the tubular sills, the trusses having sockets near the ends to receive said sills and the segments near the 75 middle to serve as struts, the braces secured to one of the segments and extending and secured to the sills, respectively, to prevent distortion of the frame by the tubular sills turning in their sockets.
10. In combination with the front and rear sills and the trusses extending from front to rear, having sockets in which the sills are rigidly secured, the uprights secured rigidly to the outer truss at its ends respectively, and 80 rigidly joined at their upper part by a cross-bar, and the braces secured to the upper part of the uprights, respectively, and extending and secured to the strut of the inner truss.
12. In combination with the front and rear sills and the trusses extending from front to rear, having sockets in which the sills are rigidly secured, the uprights secured rigidly to the outer truss at its ends respectively, and 85 rigidly joined at their upper part by a cross-bar, and the braces secured to the upper part of the uprights, respectively, and extending and secured to the strut of the inner truss.
13. In combination with the trusses, the 90 front and rear sills and the outer uprights rigidly secured thereto, the cross-bar connecting said uprights, and the braces P', P², P³, and P⁴, joined to the upper part of the strut of the inner truss, and extending and secured, 95 two of them to the outer uprights, respectively, and two of them to the sills, respectively.
14. In combination with the front and rear sills, rigidly connected, the outer uprights 100 rigidly joined thereto, and the elevator-slide bearing-bars rigidly joined to the uprights and to the sills, respectively, and the elevator-rollers journaled in the slide bearing-bars, whereby the elevator mechanism is supported independent of the sheathing, substantially as set forth.
15. In combination with the front and rear sills, rigidly connected, the outer uprights rigidly joined thereto, and the slant-bars O⁵ O⁶, 110 rigidly connected to the uprights and to the sills, respectively, whereby are formed a pair of upright triangular frames to support the elevator mechanism.
16. In combination with the front and rear 115 sills, rigidly connected, the outer uprights rigidly joined thereto, the elevator-slide bearing-bars secured to the uprights and to the sills, respectively, the elevator-rollers journaled in the slide bearing-bars, and the sheathing made 120 of sheet metal secured to the outer surface of the slide bearing-bars.
17. In combination with the front and rear sills, rigidly connected, the uprights M', M², M³, and M⁴, rigidly secured two to each sill, 125 and the elevator-slide bearing-bars rigidly secured, two to the rear uprights and two to the front uprights, and the sheathing of sheet metal secured between the uprights and the slide bearing-bars, which are secured to them 130 respectively.
18. In combination with the front and rear sills, the uprights M³ M⁴, made of metal bar and affording support and attachment for the

elevator-slide bearing-bars, and bent horizontally inward from such attachment, and the seat-plank secured on said horizontal portions.

5 19. In combination with the sickle crank-shaft journaled outside the wheel and having the crank in front of the front sill, the front truss-clip, D^t, of the inner truss, having the pivot for the pole, and the aperture between 10 said pivot and the front sill for the sickle crank-pitman.

20. In combination with the metallic rear sill and the under flooring of the conveyer-platform, the wooden plank S', secured to the

metallic sill and having the flooring secured 15 to the lower edge, and serving as a hanger to connect the sill and the flooring, substantially as set forth.

In testimony whereof we have hereunto set our hands, in the presence of two witnesses, 20 at Chicago, Illinois.

HERMAN N. KENNEDY.
BURR A. KENNEDY.
